UNITED STATES PATENT OFFICE.

WILLIAM J. WINAS, OF SAGINAW, MICHIGAN.

ADJUSTABLE SUPPORT FOR SHADE-ROLLERS.

No. 909,269.

Specification of Letters Patent.

Patented Jan. 12, 1909.

Application filed March 2, 1908. Serial No. 418,842.

To all whom it may concern:

Be it known that I, WILLIAM J. WINAS, a citizen of the United States, residing at Saginaw, in the county of Saginaw and State of Michigan, have invented certain new and useful Improvements in Adjustable Supports for Shade-Rollers; and I do hereby declare the following to be a full, clear, and exact description of the invention, such as will enable others skilled in the art to which it appertains to make and use the same.

My invention relates to adjustable supports for shade rollers, one object being to provide a simple, inexpensive and durable device of such construction as to permit the shade fixtures to be adjusted to support shade rollers of varying lengths.

Another object is the provision of a support for both shade fixtures and curtain poles.

To these and other ends, therefore, my invention consists in certain novel features and combinations of parts, such as will be more fully described hereinafter and particularly pointed out in the claims.

In the accompanying drawings, Figure 1 is a perspective view showing my invention applied to a window casing; Fig. 2 is a detail view of the curtain pole supporting arm; and Fig. 3 is an end view of one of the adjustable supports showing a curtain fixture and a curtain pole supporting arm.

Heretofore considerable work has been necessary in fastening the independent curtain fixtures to the window casing at such distance apart as to receive a shade roller of a certain length. Furthermore, it is customary for landlords to furnish shades and fixtures in place for the tenants, in order that the latter may not have to mar and injure the wood-work by fastening fixtures at different points thereon to accommodate different lengths of shade rollers.

My invention avoids the labor incident to correctly locating the individual shade fixtures and is adjustable to accommodate different lengths of shade rollers, thus avoiding the necessity of injuring the appearance of the window casing. Another advantage is that the curtain pole supports are removably attached to the base plates and may be removed in case curtains are not used. A further advantage is that the curtain pole supports are adapted for either poles or the apertured extension rods in common use.

In carrying out my invention, I provide a

pair of base plates (1) (1) to be fastened at or near the opposite upper corners of a window casing (A). I prefer to place the base plates at the upper outer edges of the casing so that a curtain supported on the pole will conceal the adjustable fixture. The description of one of these plates and its associated parts will suffice for both.

The longitudinal edges of the base plate (1) are bent over to form the ways or guides (2) (2) adapted to slidably receive the foot (3) of a curtain fixture (4). The foot (3) carries a set or binding-screw (6), the end of which screw takes against the base plate to releasably retain the fixture in any adjusted position. The fixture (4) projects outward from the base-plate and the foot at right-angles thereto and supports one end of a shade roller in the usual manner. The fixtures (4) (4) slidably adjustable toward and from each other in their respective base plates will accommodate any of the usual lengths of shade rollers without necessitating the removal of the means for fastening the base plates to the casing.

It is obvious that the base plates and fixtures are capable of use alone, but for convenience, I prefer to utilize the base plates as brackets for curtain pole or rod supports.

As one form of curtain pole or rod support, I may employ the arms (7) (7) which may be of any suitable construction, but I prefer to make them of heavy wire bent into an L-shape. The vertically-extending supporting standard (8) of each arm is preferably flattened as at (9) and received in alined apertures (10) (10) formed in the respective upper and lower guides (2) (2) of each base plate (1), whereby the arms are supported at two points and held stationary. These standards may serve as stops to limit the movement of the shade fixtures in one direction. I preferably form a shoulder (11) on each standard which shoulder engages the guide (2) to support the arm at the proper height above the base plate.

The outer end of the arm (7) is provided with a cradle or hook (12) adapted to receive curtain poles of large size. In case curtain rods having apertures therethrough are employed the outer ends of the arms are receivable in such apertures.

It will be seen that I have provided a curtain pole and shade roller support which is simple in construction. The supports (7) can be removed when not in use without

marring the appearance of the adjustable support and it will be noticed also that the base plate is formed of a single piece of material.

5 Having thus fully disclosed my invention, what I claim as new is—

1. The combination with a base plate having guides, of a curtain fixture adjustably received between the guides, the guides having 10 alined apertures formed therein, a curtain pole support, the standard of which is flattened and received in the alined apertures in front of the base plate, and a shoulder on the standard adapted to engage one of the guides 15 to limit the movement of the standard in one direction.

2. An adjustable support for shade rollers comprising a smooth base plate, guides on the plate, a curtain fixture, the foot of which 20 is overlapped by the guides and rests against the smooth base plate, a set screw carried by the foot and adapted to bind against the surface of the base plate, the guides having

alined apertures, a curtain pole support, one end of which is received in the apertures and 25 a shoulder located intermediate the ends of the curtain pole support, the shoulder adapted to engage one of the guides to limit the movement of the curtain pole support in one direction.

3. The combination with a base plate having guides, of a curtain fixture adjustably received between the guides, the guides having 30 alined apertures formed therein, a curtain pole support, the standard of which is received in the alined apertures in front of the base plate, and a shoulder on the standard adapted to engage one of the guides to limit the movement of the standard in one direction.

40 In testimony whereof, I affix my signature in presence of two witnesses.

WILLIAM J. WINAS.
